United States Patent

Des. 236,717
Patented Sept. 9, 1975

236,717

PREFOAMED EXPANSION JOINT

William J. Patterson, Burlington, Iowa, assignor to Midwest Manufacturing Corporation, Burlington, Iowa

Filed Mar. 26, 1974, Ser. No. 454,948

Term of patent 14 years

Int. Cl. D25—01

U.S. Cl. D13—6

FIG. 1 is a perspective view of a prefoamed expansion joint showing my new design,

FIG. 2 is a side view of the side seen in FIG. 1.

FIG. 3 is a side view of the opposite side shown in FIG. 2,

FIG. 4 is a top view thereof,

FIG. 5 is a bottom view thereof,

FIG. 6 is an end view from the left end of FIG. 1, and

FIG. 7 is an end view of the opposite end shown in FIG. 6.

I claim:

The ornamental design for a prefoamed expansion joint, as shown and described.
